(57) **CLAIM**

The ornamental design for an rectoscope with a tube insert, as shown and described.

DESCRIPTION

FIG. 1 is a front left side isometric view of a rectoscope with a tube insert in accordance with the new design;

FIG. 2 is a left side elevation view thereof;

FIG. 3 is a right side elevation view thereof;

FIG. 4 is a top plan view thereof;

FIG. 5 is a bottom plan view thereof;

FIG. 6 is a front elevation view thereof;

FIG. 7 is a rear elevation view thereof;

FIG. 8 is a front left side isometric view of the rectoscope with a tube insert of FIG. 1, with the distal attachment piece omitted in order to show aspects of the design that are not shown in the alternate views;

FIG. 9 is a left side elevation view thereof;

FIG. 10 is a right side elevation view thereof;

FIG. 11 is a top plan view thereof;

FIG. 12 is a bottom plan view thereof;

FIG. 13 is a rear elevation view thereof;

FIG. 14 is a front elevation view thereof;

FIG. 15 is a front left side isometric view of the rectoscope with a tube insert of FIG. 1, with the proximal handle piece omitted in order to show aspects of the design that are not shown in the alternate views;

FIG. 16 is a left side elevation view thereof;

FIG. 17 is a right side elevation view thereof;

FIG. 18 is a top plan view thereof;

FIG. 19 is a bottom plan view thereof;

FIG. 20 is a front elevation view thereof; and,

FIG. 21 is a rear elevation view thereof.
